UNITED STATES PATENT OFFICE

101,575

DESIGN FOR A COMBINATION SCREW CAP AND DROPPER FOR BOTTLES

Joseph C. Windbiel, Evansville, Ind., assignor to
Mead Johnson & Company, Evansville, Ind., a
corporation of Indiana

Application August 21, 1936, Serial No. 64,504

Term of patent 14 years

To all whom it may concern:

Be it known that I, Joseph C. Windbiel, a citizen of the United States, residing at Evansville, in the county of Vanderburgh and State of Indiana, have invented a new, original, and ornamental Design for a Combination Screw Cap and Dropper for Bottles, of which the following is a specification, reference being had to the accompanying drawing forming part thereof.

In the drawing:

Fig. 1 is a perspective view of a combination

screw cap and dropper for bottles, with the closure caps in place on the dropper nozzle and air vent neck, showing my new design; and

Fig. 2 is a perspective view of the same showing the closure caps removed.

I claim:

The ornamental design for a combination screw cap and dropper for bottles as shown and described.
